CLAIM

I claim the ornamental design for a condiment basket, as shown.

DESCRIPTION

FIG. 1 is a top perspective view of a condiment basket showing my design;

FIG. 2 is a bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.
